UNITED STATES PATENT OFFICE

2,469,559

LADDER

Harold A. Johns, Chicago, Ill., assignor to Imagining Corporation, Chicago, Ill., a corporation of Illinois

Application October 29, 1945, Serial No. 625,378

4 Claims. (Cl. 228—29)

1

This invention relates to a ladder, and more particularly to a ladder of a foldable type. The invention is particularly useful in connection with a foot ladder.

An object of the invention is to provide a ladder formed of relatively few parts and which may be readily folded into collapsed and expanded positions, cooperating parts in the top portion of the ladder serving to lock the structure together into a sturdy rigid support when in expanded position. A further object is to provide a simple ladder structure which may be collapsed by grasping the top board of the ladder, and drawn to expanded position by merely moving the rails of the ladder forwardly, the top board of the ladder serving not only as a handle for collapsing the ladder but also, when the ladder is in expanded position, serving to lock the structure rigidly in supporting position. Other specific objects and advantages will appear as the specification proceeds.

The invention is illustrated, in preferred embodiments, by the accompanying drawing, in which —

Figure 1 is a side view in elevation of a ladder embodying my invention; Fig. 2, a view similar to Fig. 1 but showing the ladder in collapsed position; Fig. 3, a rear view in elevation; Fig. 4, a top plan view; and Fig. 5, a rear view in elevation of the ladder equipped with a modified form of back support.

In the illustration given, a pair of side rails 10 are connected by steps 11 and at their top engage a top board 12. A back support 13 is secured to the rear edge of the top board 12. Link members 14 connect the rails 10 and back support 13 to limit the angle of separation thereof.

The side rails A may be formed of any suitable material and configuration. In the illustration given, the rail 10 is formed from a strip metal having rolled side edges 15 which provide tubular supports and the intermediate web portion is preferably provided with elongated openings 16 which lighten the rails. Between the slots 16 cleats 17, formed of hollow metal webbing, are welded to the web portion of the side rails 10 or otherwise secured thereto. The steps 11 are also shown formed of strips of metal having rolled edges 18 providing cross beam supports and the members 18 are received within sockets provided by the cleats or step-supporting brackets 17.

The rails 10 are pivotally connected at their rear top edges at 19 to the top board 12.

The top board 12 is preferably formed of metal having a wide central web portion 20 and depend-

2

ing flanges 21. The web portion 20 is preferably provided with ribs 22 or other suitable roughening means. If desired, the forward corner portions of the web 20 and flanges 21 may be formed with resilient socket portions 23 which are adapted to frictionally engage and grip the forward top portion of the rails 10.

The back support 13 may be of any suitable construction. In the form shown in Figs. 1 to 4 inclusive, it comprises a U-shaped bar having its top portions pivotally connected to the flange 21 of the top board 12 at 24.

The connection of the back support 13 at 24 brings the back member in close relation to the flange 21, so that flange 21 is useful in providing a rigid gripping support for the back support at its top.

To limit the angle of separation between the back support 13 and the rails 10, I provide a link 14 which is pivotally connected to the back support at 25 and to the rails at 26.

The rails 10 may be provided at their base with rubber inserts 27 which prevent slipping of the rails, the inserts being secured within the tubular members 15 or in any other way secured to the rails 10.

In the modified construction shown in Fig. 5, the structure throughout is the same except for the back support. The back support shown in Fig. 5 comprises a pair of members 28 having intermediate portions bowed inwardly and secured together at 29 by spot welding, bolts, or any other suitable means, the legs being sprung apart again at the bottom and provided with rubber bases 30.

In the operation of the structure, the ladder may be moved from the collapsed position shown in Fig. 2 to expanded position by merely drawing the rails 10 forwardly. This movement causes the top board 12 to drop to the position shown in Fig. 1 and the link 14 swings to the inclined position shown in Fig. 1. When the user steps upon the ladder, the ladder automatically locks itself rigidly by bringing the flange 21 tightly about the forward edges of the rails 10. If the sockets 23 are employed, the sockets, which extend well around the forward portion of each rail 10 firmly grip the rail and lock it rigidly to the top board 12.

After use of the ladder, the user may simply grasp the forward end of the board 12 and pull it upwardly. This movement causes the rails 10 to swing to the collapsed position shown in Fig. 2. The forward flange 21 serves, in these operations, not only as a locking element to pro-

vide the desired rigidity, but also as a handle for collapsing the ladder and carrying the collapsed structure. It will be noted that in this operation no other manual movement is necessary. Since the link 14 is a single member and is not formed of two pieces connected at their center, it is not necessary to brace the link in any manner.

While in the foregoing structure, I have set forth specific details which are favored because of the new functions developed, it will be understood that changes may be made such as, for example, substituting a two-link brace pivotally connected in the center for the one-link brace 14, and also other means may be provided for locking the rails to the top board instead of the specific structure shown. I prefer, however, the specific structure illustrated because of the new functions accomplished, the extreme rigidity automatically provided by the pressure of a person upon the step in causing the flanges at top 12 to grip the rails, and the ease with which the structure may be collapsed through simply lifting the forward flange of board 12.

The modified form of back support 28 is extremely sturdy and firm while employing a relatively small amount of metal. The structure is further desirable in that the diverging feet portions provide a means for self-centering the ladder when weight is put thereon.

While in the foregoing description, I have set forth certain details illustrating a particular embodiment of the invention, it will be understood that such details may be varied widely by those skilled in the art without departing from the spirit of my invention.

I claim:

1. A ladder comprising a pair of rails, step means connecting said rails, a back support, a top board having a web wider than said rails equipped with depending flanges, said flanges providing socket portions adapted to grip the forward top portions of said rails when brought thereagainst, means pivotally connecting the rear top portions of said rails to said flanges at an intermediate point on said board to permit said rails to swing within said flanges and bring the forward top portions thereof into engagement with said flanges and permitting said rails to swing rearwardly when the front portion of the board is raised, and means connecting the back support to the rear portion of said board.

2. A ladder comprising a pair of rails, step means connecting said rails, a back support, a

top board having a web wider than said rails and equipped with depending flanges, means connecting the rear top portions of said rails to said flanges at an intermediate point on said board to permit said rails to swing within said flanges and bring the forward top portions thereof into engagement with said flanges permitting said rails to swing rearwardly when the front portion of the board is raised, and means connecting the back support to the rear portion of said board.

3. A ladder comprising a pair of rails, step means connecting said rails, a back support, a top board having a web wider than said rails and equipped with depending flanges, said flanges being adapted to grip the forward top portions of said rails when brought thereagainst, means pivotally connecting the rear top portions of said rails to said flanges at an intermediate point upon said board to permit said rails to swing within said flanges and bring the forward top portions thereof into engagement with said flanges permitting said rails to swing rearwardly when the front portion of the board is raised, and means connecting the back support to the rear portion of said board.

4. A ladder comprising a pair of rails, step means connecting said rails, a back support, a top board having a web wider than said rails and equipped with depending flanges, said flanges providing resilient socket portions adapted to grip the forward top portions of said rails when brought thereagainst, means pivotally connecting the rear top portions of said rails to said flanges at an intermediate point on said board to permit said rails to swing within said flanges and bring the forward top portions thereof into engagement with said flanges permitting said rails to swing rearwardly when the front portion of the board is raised, and means connecting the back support to the rear portion of said board.

HAROLD A. JOHNS.
